ELECTRIC GASEOUS DISCHARGE APPARATUS

André Claude, Nanterre, France

Application October 22, 1931, Serial No. 570,450
In France November 5, 1930

4 Claims. (Cl. 176—42)

The present invention relates to electric gaseous discharge apparatus containing at least one rare gas, and operating on the arc principle, and which are fed by direct or alternating current, it can be applied to apparatus of that kind which are to be used for lighting purposes.

An object of this invention is the maintenance of integrity of the cathode in all apparatus of this type over long periods and also for maintaining the constancy of the lighting power and of the quality of the light emitted by the gaseous mass contained in the apparatus. Another object of the present invention is the application of the means giving the above results to any electric gaseous discharge apparatus which is not used for lighting purposes, and for which it would be desirable to obtain one or several of the said results.

It is well-known that in a discharge apparatus of the herein above mentioned type working on the arc principle that although the drop in potential at the cathode is very low, a considerable amount of energy is absorbed by the cathode by reason of the great intensity of the current passing through the device.

The energy thus expended causes a local increase in temperature which can be sufficient to volatilize the material of which the cathode is made. *Inter alia* the volatilization is the more intense the lower the boiling point of the material of the cathode. This volatilization takes place particularly at the cathodic spot where, also, particles of the cathodic material are spat-tered off.

In order to eliminate the disadvantages due to the volatilization of the cathode material, the cathodic part of the discharge apparatus, that is to say that part of the apparatus which enshrouds the cathode, is constructed so as to form zones which, during the normal operation of the apparatus will be at a temperature sufficiently lower than that of the gas of the apparatus, than that of the sides of the luminous column and than that of the sides of the anodic region so that the cathodic material volatilized in the cathodic space can be condensed in the said zones. These zones however are at a temperature sufficiently high to cause the material which has been condensed to fall in a molten state upon the body of the cathode.

The condensation zones of the cathodic part of the apparatus can be obtained by shaping elements of the cathodic part in such a manner that

(A) Certain zones of these elements are less

subject to the effects of heat due to the electric energy absorbed at the cathode than others.

(B) Certain zones of these elements are colder than others, these last zones being formed wholly or partly by all or part of the zones mentioned under A.

Further, a region, the normal temperature of which is considerably higher than that of the luminous part and much higher than that of the condensation zones of the cathodic region is interposed between this latter and the luminous column. The effects of such an arrangement is to settle the limits of the condensation zones. It is particularly effective when the difference between the temperature of the cathodic condensation zones and the temperature of the luminous region is relatively slight.

The arrangement can be realized in different ways for example by

(A) Narrowing the luminous column at a suitable point in the same.

(B) By providing a lagging sleeve reducing cooling at the walls.

(C) By providing an auxiliary heating arrangement formed for example by means of all or part of the stabilization resistance of the feed circuit of the discharge apparatus.

(D) By providing a combination of several of the above-mentioned means.

In order to eliminate the disadvantages due to the spattering of the material of the cathode, a material obstacle is interposed between the cathode and the extreme cathodic section of the illuminating part of the gaseous column, so that no particle of material emitted in a straight line from any point of the cathode can reach the illuminating part of this column.

Consequently, as the particles emitted by the cathode are mainly projected in a straight line for substantially long stretches into rare gases or mixtures of such, even in the case of the low pressures of gas used in the electric discharge apparatus, they are stopped by this obstacle which is preferably mounted in such a way that the particles return to the cathode.

By using the above-mentioned means numerous advantages are obtained some of which are cited below.

1. The body of the cathode does not suffer any loss by conveyance of cathodic material out of the cathodic region during the operation of the discharge apparatus and it is consequently possible to considerably reduce the mass of material necessary for the formation of the cathode, for example by placing inert filling material in

the cathodic cup; these filling materials consisting of fragments or beads of glass or quartz and the like; this being particularly desirable where the cathode is formed of an alkaline earth metal, 5 alkaline earth metallic alloy or a precious metal.

2. Any condensation of cathodic matter in a non-cathodic region of the apparatus is prevented and consequently any occlusion of the gas charge of the discharge apparatus through these deposits 10 is eliminated so that on the one hand the transparency of the walls or sides of the luminous column of the apparatus is not altered and on the other hand the gaseous mass of the said apparatus is preserved unchanged.

15 The invention is more particularly described with reference to the accompanying drawing showing certain constructions by way of example.

Figure 1 is an electric light discharge device constructed according to the present invention.

20 Figure 2 is a detailed view on an enlarged scale of the cathodic part of the apparatus according to Fig. 1.

Figure 3 is a view of a first modification of the cathodic part of Fig. 2.

25 Figure 4 is a view of a second modification of the same cathodic part.

Figure 5 is a third modification of the same cathodic part.

30 Figure 6 is a fourth modification of the same cathodic part.

In the various figures, the same reference numerals indicate the same elements.

The discharge apparatus shown in Fig. 1 comprises an anodic part 1 provided with its anode 35 1°, a luminous column 2 and a cathodic part 3 with its cathode 3°.

In Figure 2 the cathodic part 3 is formed by a container 4 which is concave and fairly wide, the walls 5, 6, 7, and 8, 9, 10 of which, not subject 40 (or only slightly subject) to the effects of heat due to the discharge, form the condensation zones for the vapour of the cathodic material contained in the bowl or cup 11. The above condensation zones can also be placed outside the cathodic 45 region itself. They will consequently be colder than this, but sufficiently warm as stated above for causing the condensed matter to fall in a molten state on the cathode.

In Fig. 3, 12 shows a choke interposed between 50 the luminous column 2 and the cathodic part 3 and which forms a section 13 which is at a higher temperature than the temperature of the luminous column 2 and of the cathodic region.

In Fig. 4, 14 represents a member which can 55 be either a lagging sleeve or a heating arrangement which forms a section 12 at a temperature higher than that of the luminous column 2 and of the cathodic region.

In Fig. 5 the elbow 15 located between the positive luminous column 2 and the cathode member 3 forms a limit 16 to the cathodic material deposits tending to be projected into the apparatus in a straight line.

In Fig. 6 the screen 17 prevents the tendency 65 of particles projected in a straight line from the cathode, from falling into the tube and acts as a material obstacle to them.

It is to be understood that the various means described above and illustrated in the figures can be utilized solely or in various combinations in the same discharge apparatus.

Having now particularly described and ascertained 5 the nature of my said invention and in what manner the same is to be performed, I declare that what I claim is:—

1. An electric discharge apparatus for operation under arcing conditions comprising an envelope containing at least one rare gas and divided into communicating cathode and discharge chambers, a cathode in the cathode chamber formed of metal volatile at the temperatures to 10 which the cathode is heated by electrical energy passing therethrough in the operation of the apparatus, the portion of the cathode chamber between the discharge chamber and the cathode constituting a condensing chamber and being constructed of a size sufficiently large relative to 15 the cathode so that the walls thereof will be at a temperature lower than the boiling point and higher than the melting point of the cathode metal, means for maintaining a zone intermediate the discharge and cathode chambers at a temperature higher than that of the discharge chamber, and an obstacle between the cathode and the discharge chamber capable of preventing any particles of metal projected in a straight line from any point of the cathode from penetrating into 20 the discharge chamber.

2. Apparatus according to claim 1, in which the means for maintaining the intermediate zone at a temperature higher than that of the discharge chamber consists of an electric resistance 25 connected in series with the electric supply circuit of the apparatus.

3. Apparatus according to claim 1, in which the means for maintaining the intermediate zone at a temperature higher than that of the discharge chamber consists of heat insulating material surrounding the apparatus at said zone.

4. An electric discharge apparatus for operation under arcing conditions comprising an envelope containing at least one rare gas and divided into communicating cathode and discharge chambers, a cathode in the cathode chamber formed of material volatile at the temperatures to 40 which the cathode is heated by electrical energy passing therethrough in the operation of the apparatus, the cathode chamber being constructed sufficiently large relative to the cathode so that the wall thereof will be at a temperature higher than the fusion point and lower than the condensation point of the cathode material, means for maintaining a zone intermediate the cathode and discharge chambers at a temperature higher than the temperature of the discharge chamber and a screen positioned between 45 said zone and the cathode to prevent particles of the cathode projected in a straight line from entering the discharge chamber whereby light is emitted in the discharge chamber solely by the rare gaseous filling to the exclusion of light emitted by the material of the cathode.

ANDRÉ CLAUDE.
